UNITED STATES PATENT OFFICE

125,052

DESIGN FOR A COMBINED ASH TRAY AND SUPPORT FOR USE ON BATHTUB RIMS OR THE LIKE

Saul Goldstein, New York, N. Y.

Application May 22, 1940, Serial No. 92,520

Term of patent 14 years

To all whom it may concern:

Be it known that I, Saul Goldstein, a citizen of the United States, residing at New York city, in the county of Bronx and State of New York, have invented a new, original, and ornamental Design for a Combined Ash Tray and Support for Use on Bathtub Rims or the like, of which the following is a specification, reference being had to the accompanying drawing, forming part thereof.

Figure 1 is a side view of a combined ash tray and support for use on bathtub rims or the like, showing my new design.

Figure 2 is a front view.

Figure 3 is a top view.

I claim:

The ornamental design for a combined ash tray and support for use on bathtub rims or the like, as shown.

SAUL GOLDSTEIN.
